FIG-3

FIG. 1 is a front elevational view of the toilet, incorporating the features of my new design;

FIG. 2 is a top view of the toilet as shown in FIG. 1; and

FIG. 3 is a side view of the toilet, as seen from the left of FIG. 1.

The side not shown is substantially like the side shown.
The rear not shown is open.

The dominant features of my design reside in the portions shown in full lines.

I claim:

The ornamental design for a toilet, as shown and described.
